(57) **CLAIM**

The ornamental design for a lighting fixture as shown and described.

DESCRIPTION

FIG. 1 is a top view of the lighting fixture of the present invention.

FIG. 2 is a front elevation of the lighting fixture of the present invention.

FIG. 3 is a perspective view of the lighting fixture of the present invention; and,

FIG. 4 is a side elevation of the lighting fixture of the present invention.

The claimed design has a flat bottom that is without surface ornamentation.

The broken lines are for the purpose of illustrating features that form no part of the claimed design.
